Patented Aug. 3, 1976

240,836

PORTABLE BATTERY BOOSTER

William B. Corvette, Conyers, Ga., assignor of fractional part interest to Leonard B. Steele, Fort Lauderdale, Fla.

Filed Nov. 13, 1974, Ser. No. 523,536

Term of patent 14 years

Int. Cl. D13—02

U.S. Cl. D26—15 B

FIG 1

FIG 2

FIG 3**FIG 4****FIG 5****FIG 6**FIG. 1 is a perspective view of a portable battery booster showing my new design;

FIG. 2 is a top plan view thereof;

FIG. 3 is an elevational view of a side of the portable battery booster;

FIG. 4 is a front elevational view thereof;

FIG. 5 is an elevational view of the side of the portable battery booster opposite the side shown in FIG. 3; and

FIG. 6 is a rear elevational view thereof.

I claim:

The ornamental design for a portable battery booster, substantially as shown.
